ROTARY WING FLYING MACHINE

Claude Dornier, Friedrichshafen-on-Bodensee,
GermanyApplication January 26, 1934, Serial No. 708,395.
Renewed June 24, 1937. In Germany January
27, 1933.

2 Claims. (Cl. 244—17)

This invention relates to flying machines using common rotors for providing both lift power and propelling power, more particularly to machines having rotors consisting of a plurality of power actuated wings producing lift and propelling power for said machines and of wings actuated by the air current relative to the machine and/or of wings actuated by said power actuated wings.

5 An object of my invention resides in the provision of a flying machine having a rotor for providing lift and propelling power, said rotor consisting of a power driven and a freely rotating rotor assisting each other and minimizing the amount of power required.

10 A further object of this invention is the provision of a pneumatically operated rotor consisting of hollow wings producing lift and propelling power and driven by the reactive force of an air current circulating therein and of wings excluded from said internal air current and having most favorable aerodynamical configuration and producing lift and propelling power at best efficiency conditions.

15 An object of the present invention is to provide a flying machine having a rotor for providing lift and propelling power and the utmost of maneuvering ability combined with small power requirements.

20 An object of my invention resides in the provision of a flying machine of the type described and having means for perfectly balancing the machine and, particularly, for counteracting the torque of the rotor.

25 An object of my invention is to provide a rotor for flying machines the lift and propelling power of which is provided by a rotor system, said rotor being adapted to secure utmost maneuvering possibility.

30 An object of this invention resides in the provision of a rotor for flying machines, said rotor consisting substantially of a combination of power driven wings and wings driven by the air currents surrounding the rotor, whereby one type of wings effectively assists the other type of wings in producing the utmost in lift and propelling power and greatest maneuvering capacity.

35 Further and other objects of the present invention will be hereinafter set forth in the accompanying specification and claims and shown in the drawing which, by way of illustration, shows what I now consider to be a preferred embodiment of my invention.

40 55 In the drawing:

Fig. 1 is a part sectional side view of a flying machine according to my invention.

Fig. 2 is a sectional view of a flying machine according to my invention having a pneumatically driven rotor.

Referring more particularly to the drawing:

Fig. 1 illustrates a flying machine having a system of rotating wings providing lift as well as propelling power. The axis of rotation of the system and the horizon form an angle open in forward and upward direction when flying substantially horizontally, said angle being always greater than 0° and smaller than 90°. It must be understood that the flying machine according to my invention does not have one or more separate and individual propellers for moving forward and one or more lifting air screws for upward or downward movement, but has only one system of revolving wings serving both purposes. Large machines of the type described in this specification may be provided with a plurality of rotating wing systems having parallel axes of rotation. The rotor system consists of actively propelling wings and, partly, of wings serving other purposes, and the machine operates partly as an autogyro. Its manoeuvrability is greater than that of a machine the lift of which depends on a system of freely rotating wings only, while, on the other hand, the use of the windmill system causes a considerable saving in power. The two wing systems combined in one system may revolve in the same or in opposite directions with respect to one another. One of the systems is power driven and may be operatively connected with the other system by means of disconnectable clutches and/or gears so that one system may be mechanically driven by the other and in order to provide for a certain predetermined ratio of the individual speeds of the two systems. In the embodiment of my invention as per Fig. 1, wings 1 are rigidly connected with hollow shaft 2 which is provided at its lower end with a disconnectable coupling 3 connecting it with shaft 4 and bevel gear 5 driven by bevel gear 7 which is operated by motor 6. Shaft 10 of the freely rotating wing system 12 is carried by the bearings 8 and 9 which are disposed within the hollow shaft 2. Wings 12 are connected to shaft 10 by way of hub 11. The system of wings 12 rotates freely and coaxially with the wing system 1 under the influence of the surrounding air currents. The wings 12—12 may be movably linked to hub 11. Both systems may have different diameters as shown on Fig. 1. In the em-

bodiment of my invention illustrated by Fig. 1 the freely rotating wing system consists of an odd number of wings, which explains why one of the wings 12 appears shorter.

5 Fig. 2 illustrates a flying machine according to my invention having a rotor consisting of power driven wings and wings actuated by said power driven wings and serving to produce lift and propelling power only. The power driven wings 10 are driven by the reactive force of an air or gas current. Motor 15 operates shaft 17 via bevel gear 16. Shaft 17 directly operates blower 18 which extends into the rotor. The hollow wing 13 has reaction nozzles 20 at its end and receives 15 air under pressure from blower 18. Blower 18 may be operated so as to draw air from channel 24 and force it out through the reaction nozzles 20, or it may be operated so as to draw air in through the reaction nozzles 20 and blow it out 20 through channel 24. Guide 19 is provided in the interior of wing 13 and is of such configuration as to facilitate the air flow. Cooler 25 is located in channel 24 and is cooled by the air passing 25 through this channel. It may serve as a recooler for the cooling agent of motor 15. Wing 14 is not served by blower 18 there being a wall 21 definitely sealing the hollow part of wing 13 and preventing air escaping from or being drawn into the 30 interior of the wing except through nozzles 20. Wing 14 does not actuate the rotor and may be designed smaller than the driving wing 13. Whereas the pneumatically operated wings 13 are 35 of necessity somewhat bulky because they must accommodate in their interior an air conduit and provisions to obtain utmost power from the reactive air current, wings 14 are designed to produce the best external aerodynamic effect. In a rotor system consisting of four wings, two diametrically opposed wings are actuated by the 40 internal reactive air current, whereas the other two wings have best aerodynamical configuration and are driven by said actuated wings. This secures a well balanced condition of the whole system. A rotor having six wings is preferably 45 designed in the manner illustrated in Fig. 2 wherein the pneumatically operated wing 14 is

arranged on the same diameter as is wing 13 which is actuated by wing 14. It is also possible to arrange a plurality of coaxial rotor systems, each designed as is the system having the wings 13 and 14, or one designed as is the system having wings 13 and 14 and the other so designed as to serve for actively propelling and lift producing purposes only as is illustrated by the wing system 22-23 shown in dotted lines on Fig. 2, whereby hub 22 is rigidly connected with the 10 rotor system 13-14; it is also possible to arrange a plurality of coaxial rotors, some producing lift and propelling power in the same manner as does wing system 13-14 with or without wing system 23 rigidly connected therewith, and the others 15 serving to produce lift only as does the system 12-12 in Fig. 1.

While I believe the above described embodiments of my invention to be preferred embodiments, I wish it to be understood that I do not 20 desire to be limited to the exact details of design and construction shown and described, for obvious modifications will occur to a person skilled in the art.

What I claim is:

1. In a flying machine a wing system consisting of pneumatically operated wings and of wings driven by said operated wings, each of said pneumatically operated wings being individually connected with one of said driven wings, said operated and said driven wings having the same longitudinal axis, said axis constituting a diameter of said wing system, all of said wings rotating about the same axis of rotation.
2. In a flying machine, a body having an upper fore end and containing a power plant and room for passengers and freight, a plurality of systems of rotatable wings for supplying the lift and propelling power required by said machine, all of said systems having a common axis of rotation and projecting forwards and upwards from the upper fore end of said body, only one of said systems being connected with said power plant and driven thereby.

CLAUDE DORNIER.
